Primary Examiner—Lucy Lieberman(74) *Attorney, Agent, or Firm*—Collen IP; Donald J. Ranft(57) **CLAIM**

The ornamental design for a watch-case, as shown and described.

DESCRIPTION

FIG. 1 is a front view of my new and ornamental design for a watch-case;

FIG. 2 is a rear view thereof;

FIG. 3 is a top view thereof;

FIG. 4 is a bottom view thereof;

FIG. 5 is a right side view thereof;

FIG. 6 is a left side view thereof;

FIG. 7 is a right side perspective view thereof; and,

FIG. 8 is a left side perspective view thereof.

The portions of the watch-case shown in broken lines form no part of the claimed design.
